TANK AND INSULATING MEANS THEREFOR

Rudolph F. Goecke, Elyria, Ohio, assignor to The
Pfaudler Co., Rochester, N. Y., a corporation of
New York

Application February 16, 1938, Serial No. 190,823

3 Claims. (Cl. 220—9)

The present invention relates to fluid holding tanks and has for its object to provide improved insulating means therefor which can be economically constructed and applied to the tanks and which will effectively insulate and protect the same.

A further object of the invention is to provide for connection with fluid holding and other types of tanks separable pre-formed insulating cover sections or units constructed for ready application to and connection with the tank.

A further object of the invention is to provide an improved tank insulating jacket formed of separable cover sections and including improved finish strips for sealing the joints between the sections designed to be maintained in position on the tank by the sections whereby to avoid the use of additional securing means therefor.

A further object of the invention is to provide a plurality of unitary insulating cover sections for a tank or container so constructed that one will serve to hold another in position on the tank when the sections are properly assembled thereon.

A further object of the invention is to provide separable insulating cover sections for ready application to a tank or other receptacle which are provided with self-contained connecting parts for cooperation one with another to clamp the sections on the tank.

A further object of the invention is to provide in tanks or containers to be used for processing liquids or for other purposes, an improved insulating jacket constructed of preformed separable unitary cover sections in combination with parts of the tank designed to maintain one or more of said cover sections in position on the tank.

A further object of the invention is to provide in a fluid holding tank a plurality of preformed insulating cover sections therefor and a plurality of parts serving both as supporting means for the tank and as means for securing certain of the cover sections thereon.

To these and other ends the invention resides in certain improvements and combinations of parts, all as will be hereinafter more fully described, the novel features being pointed out in the claims at the end of the specification.

In the drawings:

Fig. 1 is a side elevation of a tank embodying the invention.

Fig. 2 is an elevation of the same as viewed from the right of Fig. 1;

Fig. 3 is a sectional elevation on line 3—3 of Fig. 1 drawn to an enlarged scale;

Fig. 4 is a horizontal section on line 4—4 of Fig. 2;

Fig. 5 is a horizontal section on line 5—5 of Fig. 2, drawn to an enlarged scale and showing the means for securing the cover sections on the tank;

Fig. 6 is a fragmentary sectional elevation drawn to an enlarged scale and showing one method of effecting cooperation between the side and end insulating cover sections to secure the latter on the bottom wall of the tank;

Fig. 7 is a perspective view of one of the pre-formed cover sheets as it appears before applying the insulation thereto;

Fig. 8 is a perspective view of a preformed sheet of insulation adapted to be applied to the inner face of the cover sheet shown in Fig. 7;

Fig. 9 is a perspective view of the bottom cover sheet showing the insulation applied thereto;

Fig. 10 is a side view of a finish strip for sealing the joints between adjacent edges of the vertical cover sections shown in Fig. 4;

Fig. 11 is a front view of the strip shown in Fig. 10;

Fig. 12 is a section on line 12—12 of Fig. 11 drawn to an enlarged scale, and

Fig. 13 is a section on line 13—13 of Fig. 11.

The same reference numerals throughout the several views indicate the same parts.

The present invention relates to improvements in tanks or containers such, for example, as those intended for use in the heating and cooling of fluids or liquids, the pasteurizing of milk and cream, or the mixing, blending and sterilizing of various food products, including fruit juices, syrups, and other materials.

One important feature of the invention is to provide in combination with a tank or container, pre-formed insulating cover sections therefor which are reconstructed for ready application thereto, and which are preferably provided with self-contained means for connecting the sections one with another and for securing them in position on the container, the latter, however, constituting a complete operating unit, which may be used either with or without the insulating cover sections, depending on whether or not the material of the container is to be treated or processed by heating and cooling the same.

Referring to the drawings, the tank is designated generally by the reference numeral 10 and comprises a container 11 substantially surrounded by a jacket 12 affording a chamber 13 having an inlet 14 and an outlet 15 through which heating or cooling fluid may be passed to 55

heat or cool the bottom and side walls of the container when desired. The jacket is provided near its upper end with a connection 16 for the reception of a safety valve, not shown. The upper end 5 of the jacket is extended into engagement with the container and is welded thereto, as shown at 17 in Fig. 3. The container is provided with a fluid tight cover or closure 18 of any suitable design which may be hinged to or otherwise connected with the container.

Attached to the bottom wall 12a of the tank jacket are a plurality of supporting legs each comprising a short section 19 welded or otherwise secured to said wall, and a relatively long 15 section 20 threadedly connected with the section 19 for removal therefrom when desired, the sections 20 each being provided with a foot 21 as shown in Fig. 3. The container 11 is provided with a downwardly inclined self-draining outlet 20 extension 22 with which is connected a suitable discharge valve 23.

The insulating jacket of the tank is formed of a plurality of side or vertical cover sections designated generally by the reference numerals 24 and 25, Figs. 4 and 5, and an end cover section 26 at the bottom of the tank, Figs. 3 and 9. The vertical sections are each formed of a semi-circular sheet 27 having at its lower end a substantially channel-shaped member 28 provided 30 with an inwardly turned flange 29, Figs. 3 and 7. The upper end of the sheet 27 is provided with an inwardly extending semi-circular member 30 having a lower flange 31 welded to or otherwise secured upon said sheet and an upstanding 35 flange 32 which is adapted to rest against the container 13 and which preferably abuts a shoulder 11a thereon in the form of a bead which serves to properly position the vertical insulating sections 24 and 25 on the tank so that the flanges 40 29 thereof will assume proper relation relative to the edge of the end section 26 when being moved into supporting relation relative thereto. One of the circular sheets 27 is provided with an opening 33 for the reception of a ring 34 adapted to 45 surround the valve connection 16 and to close the opening through which it extends.

Secured within the semi-circular sheet 27 is a correspondingly shaped sheet of insulating material 35 which may be formed of corkboard or other suitable insulating material, said sheet being secured to the inner face of the semi-circular sheet 27 preferably by cement, as indicated at 50 36 in Fig. 6.

The upper end of one of the sheets of insulation is provided with an opening 37 to receive the fixture 16 on the container when the cover section 25 is applied to the jacket 12 of the container. The insulating sheet of the opposite cover section is also provided with an opening as indicated at 38 to receive a finish plate or ring 39 60 suitably secured within the opening formed in the lower end of the circular sheet 27 of the cover section 24, as shown in Fig. 3.

The insulating end cover section 26 of the tank 65 comprises a sheet of metal 40 on which is secured a sheet of insulating material 41 which may be corkboard or other suitable insulating material, said sheet being preferably secured to the metal sheet by means of cement, as indicated at 42 in Fig. 6. It will be noted that the sheet of insulation 41 is of less diameter than the metal sheet 40 so that the latter has an exposed annular portion 40a, the edge of which is seated on the inwardly turned flanges 29 of the semi-circular 75 sheets 27 and the remaining portion of which

forms a seat for the lower ends of the semi-circular sheets of insulation 35 of the cover sections 24 and 25, as shown in Figs. 3 and 6.

The end cover section 26 of the insulating tank jacket is, therefore, supported not only by the flanges 29 of the vertical sheets 27 but is also by the flanges 20a of the sections 20 of the tank legs when said sections are screwed into position on the fixed sections 19, as shown in Fig. 3. The metal sheet 40 of the end cover section 26 is provided with openings 43 for the reception of the upper ends of the leg sections 20, and the sheet of insulating material 41 is provided with corresponding openings 43a, as shown in Fig. 9.

The metal and insulating sheets 40 and 41 are 15 also provided with aligned openings 44 and 44a, respectively, Fig. 9, for the reception of the outlet member 15 extending downwardly from the bottom wall 12a of the steam jacket surrounding the container 11. Likewise the metal and insulating 20 sheets 40 and 41 are provided with aligned openings 45 and 45a, respectively, for the reception of the steam inlet member 14 which extends downwardly from the bottom wall 12a of the steam jacket, said inlet and outlet members having 25 suitable valves, not shown, connected therewith for controlling the flow of steam or other fluid or liquid to and from the jacket surrounding the container.

The means for sealing the joints between the 30 adjacent edges of the vertical cover sheets of the insulating sections 24 and 25 is in the form of a finish strip, as shown in Figs. 10 to 13, inclusive. The strip is designated generally by the reference numeral 46 and is formed of a thin sheet of 35 metal which for the greater portion of its length is doubled back upon itself and bent to form the oppositely disposed channel shaped members 47, within which the vertical edge portions 27a of the cover sheets 27 are disposed, as shown in 40 Figs. 4 and 5. The upper end of the strip 46 has an inwardly offset portion 48 on the opposite sides of which are formed channel members 49 similar to the channel members 47 of Fig. 12. The channel members 49 are adapted to receive 45 the end portions 30a of the inwardly extending members 30 on the upper ends of the semi-circular cover sheets 27 when the latter are in assembled relation, as shown in Figs. 1 and 2. The upper extremity 50 of the portion 48 of the strip 50 is parallel to the body of the latter and is adapted to rest on the flange 32 of the member 30 as shown in Fig. 1. The lower end 51 of the finish strip is offset outwardly as shown in Fig. 10, and has its side portions 51a bent down upon itself as 55 shown in Fig. 13, said offset portions overlying the channels 28 of the circular cover sheets 27, as shown in Figs. 1 and 2. With the edges 27a of the sheets 27 extended within the channels 47 of the finish strips, as shown in Fig. 5, it will be seen that the space between said edges is 60 completely closed and sealed so that dirt and other foreign matter will be prevented from passing between and behind said cover sheets.

The means for securing the insulating cover 65 sections 24 and 25 on the outer wall of the tank comprises a pair of clamping members 52 and 53, connected by screws 54 with the semi-circular sheets 27 of said sections, as shown in Fig. 5. The clamping member 52 is provided with a 70 recess 55 for the reception of a lug 56 on the member 53, a screw 57 being extended through the free end of the member 52 into the recess 55 thereof to engage the lug 56 of the member 53 in a depression formed therein. It will be seen 75

that by turning the screws 57 at opposite sides of the tank that the clamping members of each pair will be moved one in the direction of another to tightly clamp the insulating sections 24 and 25 upon the outer wall of the tank. Furthermore, when this has been done the finish strips 46 will be held in position through frictional engagement of the channel portions 47 thereof with the edges 27a of the circular cover sheets 27.

10 From the construction shown and described it will be readily apparent that the insulating cover sections 24 and 25 constitute unitary structures which include the means by which they are connected one with another and are secured upon

15 the tank, whereby the application of bolts or other parts to the tank for connecting the sections therewith is made unnecessary. This is also true with respect to the finish strips 46 which are supported entirely by the vertical edge portions of 20 the cover sheets 27 and the extensions 30 thereon.

When applying the insulating sections 24 and 25 to the tank the finish strips 46 will be held in position to permit the opposing edges of the sections to enter the channels of the strips, after 25 which, by tightening the screws 57, the sections will be drawn together and the sheets of insulation 35 urged into engagement with the tank to protect the latter, whereby to maintain more uniform temperatures within the heating or cooling 30 chamber 13 surrounding the container 11.

It will be understood that the bottom insulating section 26 is held in position not only by the flanges 29 of the semi-circular cover sheets 27, but also by the flanges 20a of the tank legs 20 35 after the latter have been screwed into position upon the members 19 which are permanently connected with the bottom wall 12a of the jacket surrounding the container.

One advantage of the present invention lies in 40 the construction of the cover sections 24, 25, and 26, in such a manner that they will be held in assembled relation upon the tank through co-operation of parts of one with parts of another, such, for example, as the clamping members 52 and 53 and associated parts which are permanently connected with the sections, thus avoiding 45 the use of separate or loose parts for this purpose. Moreover, the finish strips for sealing the joints between the cover sections are so constructed and applied thereto as not to require the use of bolts or other detachable securing parts.

Another advantage of the present construction 50 is that the legs of the tank are designed to support the same regardless of whether or not the insulating cover sections are applied thereto, the legs also serving to hold the bottom cover section in position upon the tank when the tank is to be insulated by use of the sections.

A further advantage results from interconnecting the unitary insulating sections and finish strips so as to insure coaction between the same for the purpose of maintaining the strips in position upon the tank or container, but in a manner which will permit them to be quickly applied to and removed from the tank when desired.

While the tank shown is provided with only two vertical cover sections, it will be understood that the insulating jacket may be formed of a greater number of such sections if desired and with a corresponding number of finish strips for sealing the joints between the sections.

It will be further understood that the tank proper can be purchased without the insulating jacket and that subsequently, if the user desires to treat material therein of a nature requiring the tank to be insulated he can purchase the desired number of insulating sections and easily apply them to the tank in a very short time and without difficulty.

I claim:

1. In apparatus of the class described, a tank having side and bottom walls, legs for supporting the tank detachably connected with the bottom wall thereof, said legs each having a projecting portion spaced from said bottom wall, an insulating end section on said bottom wall in engagement with and supported by the projecting portions of said legs, a plurality of separable preformed insulating cover sections on the side wall of the tank connected with said end section, and means connecting said cover sections and serving to secure them on the tank.

2. In apparatus of the class described, a tank having side and bottom walls, legs for supporting the tank detachably connected with said bottom wall and having projecting portions spaced from said bottom wall, an insulating end section on said bottom wall in engagement with and supported by the projecting portions of said legs, a plurality of preformed separable insulating cover sections on the side wall of the tank each having an inwardly turned flange extending beneath and in supporting engagement with a portion of said end section, and means serving to secure said cover sections on the tank.

3. In a tank construction wherein a vat is provided with a wall, insulating means for said wall comprising a plurality of separate insulating sections to form the side walls, each of said insulating sections comprising a cover part and an insulating part secured to the cover part, each of said insulating sections having an inwardly turned flange on the lower portion of said cover part extending below the insulating part, an end insulating section having a cover part and an insulating part, the insulating part being of slightly less area than the cover part to thereby form a flange around the end insulating section and the insulating part being secured to the cover part, said sections being fitted together with the flange of the end insulating section lying on the flanges of the side insulating sections, and the insulating portions of the side sections engaging the upper surface of the flange on the end section, means for securing said side insulating sections to each other and to said wall, a plurality of legs for said tank, and means in connection with said legs for securing said end insulating section to said wall.

RUDOLPH F. GOECKE.
